UNITED STATES PATENT OFFICE

99,612

DESIGN FOR A SWITCH HANDLE

Carl W. Sundberg and Montgomery Ferar, Detroit, Mich., assignors to Bulldog Electric Products Company, Detroit, Mich.

Application March 16, 1936, Serial No. 61,663

Term of patent 14 years

To all whom it may concern:

Be it known that we, Carl W. Sundberg and Montgomery Ferar, citizens of United States and residents of Detroit, Michigan, have invented a new, original, and ornamental Design for a Switch Handle, of which the following is a specification, reference being had therein to the accompanying drawing.

In the drawing,

Fig. 1 is a front view of the handle, showing the novel design;

Fig. 2 is a side view as if from the right of Fig. 1.

We claim:

The ornamental design for a switch handle, substantially as shown.

In testimony whereof we affix our signatures.

CARL W. SUNDBERG.
MONTGOMERY FERAR.
